UNITED STATES PATENT OFFICE

HOMER EASTERDAY, OF KANSAS CITY, MISSOURI, ASSIGNOR, BY MESNE ASSIGNMENTS,
TO POINT-O-PURCHASE COMPANY, OF KANSAS CITY, MISSOURI, A CORPORATION OF
MISSOURI

DESIGN FOR A CHAIR

Application filed February 15, 1932. Serial No. 42,858. Term of patent 7 years.

To all whom it may concern:

Be it known that I, HOMER EASTERDAY, a citizen of the United States, residing at Kansas City, in the county of Jackson and State of Missouri, have invented a new, original, and ornamental Design for a Chair, of which the following is a specification, reference being had to the accompanying drawings, forming a part thereof.

Figure 1 is a perspective view of a chair embodying my new design, and

Fig. 2 is a side elevational view of the same on a reduced scale.

Fig. 3 is an enlarged, cross sectional view of a leg of the chair embodying the design.

I claim:

The ornamental design for a chair as shown.

HOMER EASTERDAY.
